LESLIE F. BARNUM, OF DETROIT, MICHIGAN

PAPER REED

Application filed March 28, 1932. Serial No. 601,602.

The present invention relates to a novel paper tacking strip and the method of making the same.

In constructing automobile body frames and cushion spring frames metal channel members are commonly used and in order that the upholstering material may be conveniently attached thereto there is usually provided a wood or fibrous composition insert 10 strip that is inserted and secured in the channels so that the upholstering material may be tacked thereto. The present invention has as its primary object to provide such a tacking strip formed of several strands or ribbons of spirally wound paper which form a continuous 15 strip that is compressed between rollers to form it to the required cross sectional shape and size.

Another object of the present invention is 20 to provide a paper tacking strip having a core formed of spirally twisted paper strands or ribbons and to surround said core with paper strands or ribbons that are twisted in the opposite direction. Because of the present 25 manner of twisting the paper the finished strip has no tendency to unwind or assume a corkscrew shape after the manner of a paper tacking strip that is formed of strands or ribbons that are all twisted in the same direction. When the conventionally twisted 30 paper strip is inserted in a metal channel the tendency of the paper strip to assume a corkscrew shape distorts the metal channel in such a way as to make assembly of the channel into 35 the body frame difficult and sometimes impossible and the present strip which avoids all tendency of twisting facilitates rapid assembly of the channel members into the automobile frames.

Another object of the present invention is 40 to provide a method of forming reeds for basket work and the like, from paper strips or ribbons in a manner whereby a very compact article is provided which will not warp or twist as a result of stresses resulting from the particular manner in which it is formed by twisting such paper strips or ribbons.

With the above and other ends in view the 45 invention consists in matters hereinafter set forth and more particularly pointed out in

the appended claims, reference being had to the accompanying drawing, in which

Figure 1 is a vertical cross sectional view 55 of a machine for forming the present tacking strip;

Fig. 2 is a cross sectional view taken along the lines 2—2 of Fig. 1;

Fig. 3 is a diagrammatic view illustrating 60 the manner in which the paper ribbons are moistened;

Fig. 4 is a view of a fragment of the strip still in an unfinished stage, showing the paper ribbons partly unwound in order that the progressive manner in which they combine to 65 form the reed may be illustrated;

Fig. 5 illustrates the reed or strip in a finished stage, and

Fig. 6 illustrates a tacking strip having a different cross sectional shape.

Like characters of reference are employed 70 throughout to designate corresponding parts.

A pair of disks 1 and 2 are secured in spaced relation by rods 3. The disk 1 is provided with a spindle 4 that is rotatably received in a vertical frame member 5 and the disk 2 is provided with a hollow spindle 6 that is received in a vertical frame member 7. A similar pair of disks 8 and 9 are secured in spaced relation by rods 10 and are provided with hollow spindles 11 and 12 respectively. The spindles 11 and 12 are rotatably received 75 in vertical frame members 13 that are adapted to support the spindles 11 and 12 in co-axial alignment with the spindles 4 and 6. A sprocket 14 is secured on the spindle 6 and a sprocket 15 is secured on the hollow spindle 12. A sleeve 16 having a smoothly rounded head 17 is slipped into the inner end of the hollow spindles 6 and 12 in order to present 80 a smooth entering end through which paper ribbons pass in a manner presently to be described without tearing the same.

A motor 18 is connected to a shaft 19 upon which is mounted a sprocket 20 that is connected by a chain 21 to the sprocket 14. A 95 gear 22 is mounted on the shaft 19 and meshes with a gear 23 on a shaft 24 that carries a sprocket 25 which is connected by a chain 25' to the sprocket 15. It is obvious that by driving the sprocket 25 through the gears 100

22 and 23 that it rotates in an opposite direction to the sprocket 20 and therefore when the motor 18 is set in motion to rotate the shaft 19 the set of disks 1 and 2 are rotated 5 in the opposite direction to the set of disks 8 and 9.

Mounted on each of the rods 3 is a roll 26 of paper ribbon and mounted on each rod 10 is a roll 27 of paper ribbon. Before mounting the paper rolls 26 and 27 on their respective rods 3 and 10 they are moistened in the manner illustrated in Fig. 3 wherein the ribbon 28 is unrolled from the shaft 29 onto the shaft 30 and is passed under the roller 31 that 15 forces the ribbon into the tank 32 so that it contacts with the liquid 33 contained therein. The shafts 29 and 30 are rotated at a high rate of speed that prevents the ribbon remaining in the liquid long enough to absorb 20 a very great amount thereof.

A pair of rollers 34 are supported adjacent the end of the spindle 12 by any suitable frame members (not shown). One of the rollers carries a sprocket 35 over which a 25 chain 36 passes. The chain 36 engages a sprocket 37 that is connected to a bevelled gear 38 that meshes with a bevelled gear 39 on the shaft 19.

In order to commence manufacture of the 30 present tacking strip it is necessary to draw the ends of the ribbons 26 through the spindle 6 manually and then rotate the disks 1 and 2 while the ends of the ribbons 26 are held against rotation which forms a spirally 35 twisted rope 40. When sufficient rope 40 has been formed it is threaded through the hollow spindles 11 and 12. As the rope 40 is drawn through the spindle 12 the ends of the ribbons 27 are drawn with it and by rotating 40 the disks 8 and 9 the ribbons 27 are twisted spirally around the rope 40 and thus combine to form a larger rope 41 of oppositely twisted ribbons which is passed between the rollers 34. After the end of the rope 34 has been 45 passed between the rollers 34 the same prevent rotation thereof and by starting the motor 19 the rollers 34 are rotated thereby and tend to draw the rope outwardly. Movement of the rope outwardly can only be permitted by unrolling of the ribbons 26 and as 50 the ribbons unroll the set of disks 1 and 2 are rotated in one direction through the above described drive connections and thereby twist said ribbons spirally to form a continuous 55 rope 40. The rope 40 is at the same time drawn through the spindle 12 and the disks 8 and 9 are rotating in the opposite direction to the disks 1 and 2 and therefore cause the ribbon 27 to be wound in an opposite spiral 60 around the rope 40.

As the rope 41 passes between the rollers 34 it is compressed and formed in any shape or size desired as illustrated in Figures 5 and 6 wherein the strip 42 is provided with a 65 raised portion 43 which can be conveniently

observed through the fabric by the upholstery tacker while the strip 44 is of rectangular cross section.

The manner in which the several ribbons are wound in the finished article is clearly 70 shown in Fig. 4 which illustrates the present strip still unfinished in that it has not been compressed to its final shape. The several ribbons 26 and 27 which go to make the strip are shown partly unwound again after having 75 once been completed in order that the particular construction and method of manufacture of the present strip may be readily understood.

Paper ordinarily twisted to form a strip 80 does not tend to unwind by becoming loose but the stresses resulting from the twisted paper causes the finished strip to assume a corkscrew shape. The present strip avoids the possibility of such distortion by forming 85 the strip of two oppositely wound sections and therefore the stresses that tend to distort the strip are exerted in opposite directions and therefore neutralize each other.

Although a specific embodiment of the 90 present invention has been illustrated and described it is to be understood that various changes may be made in the details of construction without departing from the spirit of the invention, and such changes are contemplated.

What I claim is:

A tacking strip comprising a rope core formed of spirally twisted paper ribbons, and an outer covering formed of paper ribbons 100 twisted spirally in a direction opposite to the ribbons of said rope core.

In testimony whereof I affix my signature.

LESLIE F. BARNUM.
